PORTRABLE MOTORIZED CART

Edward N. Brennan, Tacoma, Wash. (10689D Maplewood Road, Cupertino, Calif. 95014), and Brian L. Brennan, 11616 Gorham Ave. 6, Los Angeles, Calif. 90049

Filed Apr. 17, 1969, Ser. No. 16,798

Term of patent 14 years

Int. Cl. D12—08

U.S. Cl. D14—3

FIG. 1

FIG. 2

FIG. 3

FIG. 4

FIG. 5

FIG. 6

FIG. 1 is a right side view of a portable motorized cart showing our new design ready for use;

FIG. 2 is a front view of the portable motorized cart of FIG. 1;

FIG. 3 is a left side view of the portable motorized cart of FIG. 1;

FIG. 4 is a rear view of the portable motorized cart of FIG. 1;

FIG. 5 is a left side view of the portable motorized cart of FIG. 1 ready for its portable transport; and

FIG. 6 is a top view of the portable motorized cart ready for use as shown in FIG. 1.

We claim:

The ornamental design for a portable motorized cart, as shown and described.
